[57] CLAIM

The ornamental design for medicinal herb treatment device,
as shown and described.

DESCRIPTION

FIG. 1 is a perspective view of a medicinal herb treatment device showing my new design;

FIG. 2 is a front elevational view showing one side thereof;

FIG. 3 is a rear elevational view showing another side thereof;

FIG. 4 is a right side view showing another side thereof;

FIG. 5 is a left side view showing another side thereof;

FIG. 6 is a top plan view thereof;

FIG. 7 is a bottom view thereof;

FIG. 8 is a perspective view thereof, with the cover in open position;

FIG. 9 is a top plan view of a second embodiment of the
herbal treatment device, with all other portions being identical
to that shown in FIGS. 2-8; and,

FIG. 10 is a side elevational view thereof.

The broken line showing of the person is for illustrative
purposes only and forms no part of the claimed design.
